[57] **CLAIM**

The ornamental design for a lighting fixture for partition walls, substantially as shown and described.

DESCRIPTION

FIG. 1 is a perspective view of a lighting fixture for partition walls showing my new design;

FIG. 2 is an end view thereof on an enlarged scale, the opposite end being a mirror image;

FIG. 3 is a top view thereof on an enlarged scale;

FIG. 4 is a bottom view thereof on an enlarged scale;

FIG. 5 is a side view thereof on an enlarged scale; and

FIG. 6 is the opposite side view thereof on an enlarged scale.

The fixture is broken away in FIGS. 2 through 6 for convenience of illustration.
